WELT SUPPORT

William S. Anderson, Philadelphia, Pa., assignor
to Shoe Press Corporation, Philadelphia, Pa.,
a corporation of Delaware

Application April 26, 1935, Serial No. 18,411

5 Claims. (Cl. 12—103)

This invention relates to welt supports for supporting the welt of a welted shoe during the operation of cementing the outsole to the shoe.

In cementing an outsole to a welted shoe the contacting surfaces of the welt and the outsole are provided with suitable adhesive and then a sole-attaching pressure is applied to the outsole to firmly press the cement-coated surfaces of the welt and outsole together. This pressure is usually applied to the outsole through the medium of a sole-attaching apparatus which includes in its construction a flexible bed or pad engaging the outer face of the outsole and against which the shoe is pressed with a more or less heavy pressure.

If the welt extends beyond the upper of the shoe to any extent, as welts usually do in welted shoes, the pressure of the pad against the outer edge of the outsole tends to turn the edge of the 20 outsole and the welt upwardly toward the upper thus giving the sole a sort of roll-edge effect.

It is one of the objects of my invention to provide a novel welt support which is adapted to be attached to the shoe before the outsole is applied and which serves to support the upper surface of the welt and prevent it and the edge of the outsole from being turned or rolled up toward the upper during the application of the sole-attaching pressure to the outsole.

Another object of the invention is to provide an improved welt support which is especially designed for use by cobblers in repairing welted shoes by cementing new outsoles thereto although the device is also well adapted for use by shoe manufacturers in the manufacture of welted shoes having cement-attached soles. My improved welt support is in the form of a length of closely-coiled wire of a size to be received in the crease between the welt and the upper of a

welted shoe, said coil being provided with tack-receiving eyes adapted to receive tacks by which the welt support is attached to the shoe. Since the support is made of closely-coiled wire it is flexible and can easily be placed around the toe portion of any shoe, and because of the flexibility of the support it will fit the contour of any shoe. In using the device the operator will place it in the crease between the upper and the welt and will secure it in place by driving tacks through the tack-receiving eyes. After this welt support has been thus applied to the shoe then the sole is cemented thereto in the usual way and during the application of the sole-attaching pressure the welt support serves to hold the welt

in its correct position and prevent it from being turned or rolled upwardly.

In order to give an understanding of the invention I have illustrated in the drawing some selected embodiments of the invention which will now be described after which the novel features will be pointed out in the appended claims.

In the drawing:

Fig. 1 is a view of a welt support embodying my invention.

Figs. 2 and 3 are fragmentary sectional views through a welted shoe showing the welt support in use.

Fig. 4 is a perspective view of a shoe to which the welt support has been applied preparatory to having an outsole cemented thereto.

Fig. 5 is a sectional view of a shoe press showing a shoe therein with the sole being cemented thereto.

In the drawing 1 indicates a welted shoe having the usual upper 2 and welt 3, said welt and upper being sewed to the insole 4 by the inseam stitches 5 as is usual in welted shoes.

The outsole of the shoe is shown at 6 and it is cemented to the shoe bottom in the usual way by applying a suitable cement to the contacting faces of the welt 3 and outsole 6 and then applying a sole-attaching pressure to the outsole. This pressure can be applied conveniently through the medium of a sole press 12 such as shown in Fig. 5 and which includes a flexible bed or pad 7 which forms the top of a water-containing chamber 8, the shoe being pressed against this flexible pad 7 by means of a screw 9 screw-threaded through a nut 10 carried in the yoke 11 with which the sole press is provided. This screw 9 acts against a last member 13 having a plate portion 27 which fits the inside of the shoe.

When the sole-attaching pressure is thus applied to the outsole the flexible nature of the pad 7 tends to cause the peripheral portion of the outsole and the welt to turn or roll up thereby producing a roll-edge effect.

The welt support embodying my invention and which is intended to prevent the rolling up of the edge of the outsole is indicated at 14. This is in the form of a closely-coiled wire of an appropriate length which is of a size to be received in the crease 15 between the welt and the upper and which is provided along its length with a plurality of tack-receiving eyes adapted to receive tacks by which the device is secured to the shoe. The welt support I have shown is made in sections, there being the longer cen-

tral section 17, an intermediate section 18 at each end of the central section, and two end sections 19. The intermediate sections 18 are preferably shorter than the central section 17 and the end sections 19 are shorter still. The central section 17 is formed at each end with an eye 16 which is interlinked with a similar eye 20 formed on the adjacent end of the intermediate section 18. The outer ends of the intermediate sections 18 are provided with eyes 21 which are interlinked with similar eyes 22 on the inner ends of the end sections 19. The outer end of each end section is shown as being formed with an eye 23. These eyes can be made from the ends of the wire from which the various sections are formed. In using the device the operator will place the central section 17 in the crease 15 around the toe portion of the shoe 1, and while holding said central portion tightly against the shoe he will drive tacks 24 through the eyes 16 or 20 thereby anchoring the central section of the support in place. The intermediate sections 18 are then laid along the crease 15 at the sides of the shoe and other tacks 25 are driven through the eyes 21 or 22 thus holding the intermediate portions of the support in place.

If the shoe is a large shoe so that there are still portions of the welt needing support beyond that which is supported by the intermediate sections 18 then the end sections 19 will be laid in the crease 15 and tacked in position by suitable tacks 26. If the shoe is a small shoe it may be that the central section 17 and the intermediate sections 18 will be sufficient to properly support the welt in which case the end sections 19 may be left hanging.

This support can be readily applied to the shoe by an operator in a factory or by a cobbler repairing the shoe and when it is thus applied the shoe is ready to have the outsole 6 attached in the usual way.

During the application of the sole-attaching pressure the welt support 14 serves to support the upper face of the welt and prevent it from curling upwardly so that the sole and the welt will be maintained in their correct position during the sole-attaching operation. The device embodying my invention is simple and easily used and it requires no special tools or machines to apply it to the shoe.

The wire used in making the welt support 14 may be of any suitable material. I will preferably use spring wire to give the welt support resiliency so that it will not take a set when

it is bent around the toe of the shoe, but will, when removed from the shoe, resume its normal straight condition shown in Fig. 1. I will preferably also make the wire of some rust resisting material, for which purpose the wire may be made entirely of rust resisting material or may be coated with such material. I find that chromium steel is excellent material for making the wire but the invention is not limited to the use of any particular kind of metal.

I claim.

1. A welt support for supporting a welt while cementing an outsole to a welted shoe, said welt support comprising a length of closely-coiled wire of a size to be received in the crease 15 between the welt and the upper of a shoe and provided with tack-receiving eyes to receive tacks to attach the support to the shoe.

2. A welt support for supporting a welt while cementing an outsole to a welted shoe, said welt support comprising a length of closely-coiled wire of a size to be received in the crease 15 between the welt and the upper of a shoe and provided with a plurality of tack-receiving eyes distributed along its length and adapted to receive tacks to attach the support to the shoe.

3. A welt support for supporting the welt against sole-attaching pressure, said support comprising a plurality of sections of closely-coiled wire pivotally connected together, each section being of a size to be received in the crease between the welt and the upper of a shoe, and means for attaching said support to the shoe.

4. A welt support for supporting the welt against sole-attaching pressure, said support comprising a plurality of sections of closely-coiled wire pivotally connected together, each section being of a size to be received in the crease between the welt and the upper of a shoe, the pivotal connections between the sections providing tack-receiving eyes adapted to receive tacks for attaching the support to the shoe.

5. A welt support for supporting the welt of a welted shoe against sole-attaching pressure, said support comprising a plurality of sections of closely-coiled wire of a size to be received in the crease between the welt and the upper of the shoe, each section having at each end an eye which is linked to the eye of an adjacent section, said eyes being adapted to receive tacks to attach the support to the shoe.

WILLIAM S. ANDERSON.
